UNITED STATES PATENT OFFICE.

ALEXANDER BOURASSA, OF CHICAGO HEIGHTS, ILLINOIS.

CONTINUOUS RAILWAY-RAIL.

1,064,046.

Specification of Letters Patent.

Patented June 10, 1913.

Application filed October 12, 1911. Serial No. 654,212.

To all whom it may concern:

Be it known that I, ALEXANDER BOURASSA, a citizen of the United States, and a resident of the town of Chicago Heights, 5 in the county of Cook and State of Illinois, have invented certain new and useful Improvements in Continuous Railway-Rails; and I do hereby declare that the following is a full, clear, and exact description of the 10 same, reference being had to the accompanying drawings, and to the numbers of reference marked thereon, which form a part of this specification.

Much injury is occasioned to the rolling 15 stock of railroads owing to the difficulty, if not impossibility, in affording a continuous and unvarying bearing surface at the joints. Although very many attempts have been made to afford a continuous rail joint, or 20 to afford a structure adapted to reinforce the joint between the rails to afford a continuous and comparatively unyielding surface, nevertheless practically all the rail joints prove deficient in substantially the 25 same way, that is to say, the rolling stock passing over the rail and supported upon a small bearing surface at the wheels, causes a depression at the joint so that the adjacent rail ends move up and down as each wheel 30 passes the same, soon brooming up the ties, even though protected by wear plates, permitting more or less play, which rapidly increases with time. This unquestionably is seriously aggravated by the flat spots upon 35 the wheel, which, as the wheel revolves, strike the rails a succession of practically hammer blows, soon loosening the nuts at the rail joints and putting the track in an unsatisfactory, if not dangerous condition.

40 The object of this invention is to afford a practically continuous rail in which the carrying surface is not broken at the joints, and by means of which noise and vibration is largely eliminated.

45 It is also an object of the invention to afford a construction adapting itself readily to the installation of electrical circuits and affording means to adequately protect the same from moisture and frost.

50 It is an important object of the invention to maintain a considerable degree of resiliency while affording a continuous tread surface for the rails for long distances.

The invention in its preferred form is 55 hereinafter more fully described.

In the drawings: Figure 1 is a top plan

view, broken away, of a device embodying my invention. Fig. 2 is a side elevation thereof. Fig. 3 is a section on line 3—3 of Fig. 2. Fig. 4 is an enlarged longitudinal section taken through the webs of the rails in a line with the splice bolts. Fig. 5 is an enlarged transverse section taken through the rail adjacent one of the intermediate splice bolts.

As shown in the drawings: The rails are rolled in half sections, comprising a half head member 1, a web member 2, and a flange 3, and having a plane inner face at the head and adjacent the flange and being 60 concave longitudinally for the entire length thereof on the inner side the web.

4, indicates the splice bar or plate, which is shaped transversely to fit closely in the cavity or channel between the webs, as shown 65 in Fig. 3, and is provided in one side with a longitudinal groove or recess 5, to receive electrical conductors or lead wires 6, if desired.

4^a indicates the external flat splice bar 70 with rounded edges adapted to fit snugly against the web between the head and flange on that side of the rail combination at which the end junction of two half rails occurs.

With the half rail sections so constructed, 75 the rail as a whole is built up in continuous form for any desired length by rigidly bolting the half rail sections together to bring the abutting ends of the half rail sections on one side the rail together at approximately the middle of the half rail sections forming the other side of the rail and rigidly securing the splice bar 4, therebetween by means of splice bolts 7, of the usual or any desired construction, and which 80 conveniently are provided with any suitable means such as a washer 8, or other means for locking the nuts of the splice bolts 7, in place, it being observed by reference to Fig. 4 that the internal splice bars 4 and the external splice bars 4^a are of equal length, and are disposed in register with each other.

Preferably, at the time the half rail sections are brought together in assembled relation, those portions of the channel between 95 the webs not occupied by the splice bars 4 are poured full of asphalt 9, or other suitable non-conducting and insulating means, which, investing the conducting wires 6, therein, holds the same spaced from contact 100 with the webs or head of the rail insuring satisfactory insulation and what is also im-

portant, effectually protecting the same from moisture, inasmuch as such asphaltic filling forms a cementing surface between the bearing faces of the rail sections, for 5 example, between the head sections and the flange sections. Of course, intermediate bolts 10, are provided through the webs intermediate the splice bars to rigidly hold the rail sections together as a unitary structure, and as shown, also, a clamp or chair comprising a flat plate or bar 11, to extend beneath the rail at the abutting ends of corresponding sections, is provided with upwardly turned flanges or hooks 12, to engage 15 on the oppositely disposed flanges of the rail to rigidly clamp the same in unvarying relation.

If desired, wear plates (sometimes termed "tie plates") may be provided on each tie, 20 constructed as before described to effectually clamp the rail sections together. These may be constructed, of course, of any suitable length and when engaged in place, add materially to the strength of the construction 25 and yet permit sufficient resiliency to afford a rail exceedingly easy upon rolling stock, as well as noiseless under practically all conditions of traffic.

I have shown but one (and that the preferred) form of my construction, although 30

I am aware that numerous details of construction may be varied without departing from the principles of my invention. I therefore do not purpose limiting the patent to be granted on this application other- 35 wise than necessitated by the prior art.

I claim as my invention:

A continuous railway rail constructed in half sections lapped together face to face with the joints on one side of the rail disposed intermediate the joints on the other side of said rail, splice bars disposed in channels afforded between the webs at each joint, said bars each having a wire receiving groove therein abutting the inner face of one of said half rail sections only, a filling of non-conducting material in said channels between the splice bars adapted to invest a wire, and splice bolts rigidly engaging the parts together as an unitary and continuous 45 structure and disposed outside of said wire receiving grooves.

In testimony whereof I have hereunto subscribed my name in the presence of two subscribing witnesses.

ALEXANDER BOURRASSA.
